DISH WASHING UNIT

Charles J. Manville, Pontiac, Mich., assignor to Manville Manufacturing Corp., Pontiac, Mich., a corporation

Filed Dec. 15, 1958, Ser. No. 53,781

Term of patent 14 years

(Cl. D91—3)

FIG. 1

FIG. 3

Fig. 1 is a perspective view of my dish washing unit showing my new design.

Fig. 2 is a top plan view thereof.

Fig. 3 is a reduced sectional view thereof looking in the direction of arrows 3—3 of Fig. 2 with the handle and spout members omitted for convenience of illustration.

I claim:

The ornamental design for a dish washing unit, as shown.
